MARTIN HEMLEE, OF ELIZABETH, NEW JERSEY, ASSIGNOR TO THE SINGER MANUFACTURING COMPANY, A CORPORATION OF NEW JERSEY.

DOUBLE-CHAIN-STITCH SEWING-MACHINE.

1,140,679.

Specification of Letters Patent.

Patented May 25, 1915.

Application filed January 6, 1910. Serial No. 536,748.

To all whom it may concern:

Be it known that I, MARTIN HEMLEE, a citizen of the United States, residing at Elizabeth, in the county of Union and State 5 of New Jersey, have invented certain new and useful Improvements in Double-Chain-Stitch Sewing-Machines, of which the following is a specification, reference being had therein to the accompanying drawings.

10 This invention has for its object to provide a simple and effective lower-thread mechanism for machines for producing the double-thread chain-stitch.

According to the present improvement in 15 its preferred embodiment, the machine is constructed with a main-shaft longitudinally disposed beneath the work-plate and provided with a looper-actuating eccentric embraced by the strap of an eccentric rod 20 pivotally connected with a rearwardly extending arm of a rock-lever mounted upon a transverse fulcrum beneath the main-shaft and provided with a forwardly extending arm connected by means of a short pitman 25 with the rocking looper-carrier mounted upon a fulcrum having transverse movements in the plane of its own axis which are communicated thereto by means of a second eccentric upon the main-shaft where- 30 by sidewise or needle-avoiding movements are communicated to the looper. The looper-actuating eccentric actuates the rock-lever in such manner that its forwardly extending arm moves alternately into and out of alignment with its link connection to the looper-carrier, whereby a dwell is produced in the 35 advance position of the looper.

Adjacent and in front of the main-shaft is disposed a pair of spaced thread-guiding 40 arms having alined thread-eyes between which moves a thread-controlling cam-disk fixed upon the main-shaft. The periphery of the thread-controlling cam is shaped for action in conjunction with the spaced thread-guiding eyes to control the slack looper-thread in conformity with the looper movements, excepting in the dwell of the looper in its advance position in which it retains the needle-thread loop, at which time a projection upon the thread-controlling cam-disk 50 acts to pull off a supply of looper-thread for a succeeding stitch.

In the accompanying drawings, Figure 1 is a perspective view of a machine embodying the present improvement with certain

parts omitted, others in section, and still others indicated in dotted lines only. Fig. 2 is a perspective view upon a larger scale representing a portion of the looper mechanism. Fig. 3 is a sectional elevation, looking forwardly, showing the thread-controlling device.

The machine is constructed with a frame of well known form, including the base-plate 1 from which rises the overhanging 60 bracket-arm comprising the standard 2 and lateral member 3 terminating in the head 4. The base has in its forward portion the upwardly extending bearing member 5 to which is applied in practice the work-plate 6, shown in Fig. 1 in dotted lines only. Journaled in the lower portion of the standard 2 and the bearing member 5 and beneath the work-plate 6 is the rotary main-shaft 7 carrying the usual balance-wheel 8 75 and belt-wheel 9.

As indicated more fully in my Patent No. 924,903, of June 15, 1909, the needle-actuating rock-shaft mounted in the bracket-arm has operative connections with the main-shaft common to certain of the Singer machines, and is provided at its forward end with the crank-pin 10 embraced by one end of the link 11 whose other end embraces a lateral pin upon the collar 12 fixed upon 80 the needle-bar 13 journaled in the head 4 and carrying the needle-clamp 14 in which are shown secured by means of the clamp-screw 15 the closely spaced needles 16.

Cooperating with both needles is an eyed 90 looper whose blade 17 is disposed longitudinally of the machine and whose shank 18 is secured by means of the screw 19 in a transverse seat formed therefor in the looper-carrier 20 whose lateral hub 21 is 95 formed at opposite ends with conical sockets fitted respectively to the similarly formed head 22 of the fulcrum-screw 23 and the conical bearing boss 24 upon the head 25 of the looper-supporting rock-shaft 26 journaled in the bed-plate 1 parallel with the main-shaft.

Mounted upon the main-shaft intermediate the standard 2 and bearing member 5 is the looper-actuating eccentric 27 which is 105 embraced by the strap 28 at the upper end of the eccentric-rod 29 which is formed at its lower end with a strap embracing the rearward end of a stud 30 secured by means of the nut 31 in an aperture in the rear- 110

wardly extending arm 32 of a rock-lever whose hub 33 is fulcrumed upon the pin 34 mounted in bearing lugs 35 and 36 of the bed-plate 1 beneath and transversely to the main-shaft 7. The forwardly projecting arm 37 of the rock-lever carries a stud 38 secured within an aperture therein by means of the clamp-nut 39 and having its projecting end embraced by a strap 40 at the rearward end of the link 41 whose opposite end is provided with a similar strap 42 which is fitted to and embraces the ball 43 at one end of the stud 44 secured by means of the nut 45 in a transverse aperture of the looper-carrier 20 intermediate the hub 21 and its seat for the looper shank 18. The parts are so arranged that in the extreme upper position of the actuating eccentric 27, substantially as represented in Fig. 1, the rock-lever arm 37 and its link connection 41 with the looper-carrier are approximately in alignment, while in the other extreme position of the actuating eccentric the component members of the toggle device thus formed are in their elevated relative angular arrangement at which time the looper-blade is in its extreme retracted position.

The looper-supporting rock-shaft 26 has secured upon its rearward end by means of the set-screw 46 the hub 47 of an upwardly extending forked arm 48 embracing the side-shift cam 49 fixed upon the main-shaft in a well known manner, by means of which vibratory movements are imparted to the fulcrum stud 23 in the plane of its axis and sidewise needle-avoiding movements are imparted to the looper.

Fixed upon the main-shaft intermediate the looper-actuating eccentric 27 and the standard 2 are the thread-controlling cam-disk 50 and the feed-actuating eccentric 51. The irregular marginal portion of the cam-disk 50 moves between the spaced thread-guiding arms 52 formed with the foot-piece 53 adjustably secured upon the bed by means of the fastening screw 54 and are provided with alined thread-guiding eyes 55 which are in practice separated by the margin of the disk 50 excepting at the indentation 56 50 therein, at which point the looper-thread is permitted to pass freely from one to the other without appreciable deflection.

The looper-actuating cam 27 and the thread-controlling disk 50 are fixed upon the main-shaft in such relation that the peripheral indentation 56 comes into register with the stationary thread-eyes 55 as the toggle members 37 and 41 approach their position of alignment and the looper is about to assume its advanced position, immediately after which, and while the looper remains in advance position, a pull-off projection 57 of the disk 50 adjacent the recess or indentation passes between the guide-arms 52 60 and serves while the looper is stationary to

deflect the looper-thread and pull off a supply of the same through the tension device 58 for the succeeding stitch-forming operation. The remainder of the periphery of the thread-controlling disk 50 between the pull-off portion 57 and the recess 56 is so shaped as to control the slack looper thread between the tension device and the looper to conform with the latter's operative longitudinal loop-shedding and loop-seizing movements.

In machines of this class as heretofore constructed, it has been customary to impart a comparatively long throw to the looper so that the drawing of a looper-thread supply for the succeeding stitch is effected by the advance movement of the looper terminating during the upper-thread stitch-setting operation; but the provision of a short looper stroke followed by a dwell in the present construction necessitates other means of drawing of a supply of looper thread during the take-up action upon the needle-thread, and this is done independently of the looper-actuating mechanism in the present machine 90 by means of the rotary thread-controlling cam-disk 50 as before described.

As will be seen by reference to Fig. 1, the looper-thread 1 is led from the source of supply through the tension device 58 of usual construction, and thence through a stationary thread-eye 59 upon the standard from which it passes through the eyed guide-arms 52 to the looper in a wellknown manner.

The needle-threads *n* are in practice led from the source of supply through their respective tension devices 60, thence through an adjustable thread-guide 61 upon the arm 3, through spaced guide-eyes 62 of a fixed take-up arm 63 carried by the link 11, and through eyes 64 in a thread-finger 65 upon the needle-bar whence they are led downwardly past the thread-separating pin 66 upon the needle-clamp 14 to the needle-eyes. In descending, the take-up arm 63 carries the needle-threads over the forward edge of the thread-deflecting plate 67 whose shank 68 is adjustably secured by means of the fastening screw 69 upon the head 4 of the bracket-arm, the plate 67 acting in conjunction with the other needle-thread handling devices in controlling the thread.

The machine is shown provided with the usual feeding mechanism including the feed-dog 70, and with the opposed presser-foot 71 secured upon the lower end of the presser-bar 72 pressed normally downward by means of the spring 73 in a well known manner and provided with a lifting lever 74 for raising the same.

Having thus set forth the nature of the invention, what I claim herein is:—

1. In a sewing machine, the combination with the frame and a work-plate mounted

- thereon, a rotary shaft, and a reciprocating needle operatively connected therewith, of a looper coöperating with said needle in seizing needle-thread loops therefrom and presenting looper-thread loops thereto in the production of stitches, a carrier for said looper provided with a fixed stud, a fulcrum upon which said carrier is mounted to oscillate, a rock-shaft upon which said fulcrum is supported, actuating means for said rock-shaft, a plural-armed rock-lever mounted upon a fixed fulcrum below the work-plate, a link connected at one end with an arm of said rock-lever and apertured at the other end to embrace said fixed stud of the looper-carrier, and a connection intermediate said rotary shaft and another arm of said rock-lever whereby the rock-lever is vibrated to move the first-named arm of the rock-lever and its link connection with the looper-carrier into and out of alinement for imparting operative loop-seizing and -shedding movements to the looper.
2. In a sewing machine, the combination with the frame and a work-plate mounted thereon, a rotary shaft, and a reciprocating needle operatively connected therewith, of a looper coöperating with said needle in the production of stitches, a carrier for said looper, a vibratory fulcrum for said carrier, means for imparting vibratory movements to said fulcrum, a plural-armed rock-lever mounted upon a fixed fulcrum below the work-plate, a link connection intermediate an arm of said rock-lever and the looper-carrier, and a connection intermediate said shaft and another arm of said rock-lever whereby the rock-lever is vibrated to move the first-named arm of the rock-lever and the looper-thread pull-off comprising an operative thread-engaging member fixed upon and rotating with said shaft and timed to act during the dwell of the looper in drawing off a supply of looper-thread.
3. In a sewing machine, the combination with the frame and a work-plate mounted thereon, a rotary shaft, and a reciprocating needle operatively connected therewith, of a looper coöperating with said needle in the production of stitches, a carrier for said looper, a fulcrum for said carrier disposed transversely to said shaft and movable in a plane embracing its own axis, a plural-armed rock-lever mounted upon a fixed fulcrum below the work-plate, a link connection intermediate an arm of said rock-lever and the looper-carrier, and a connection intermediate said shaft and another arm of said rock-lever whereby the rock-lever is vibrated to move the first-named arm of the rock-lever and its link connection with the looper-carrier into and out of alinement for imparting operative loop-seizing and -shedding movements to the looper.
4. In a sewing machine, the combination with the frame provided with a work-plate, a rotary shaft journaled beneath the same, and a reciprocating needle operatively connected with said shaft, of a looper coöperating with said needle in the production of stitches, looper-actuating mechanism connected with said shaft independently of the needle-actuating mechanism and including means disposed wholly beneath the work-plate for imparting to the looper an advance operative movement followed by a dwell, and a looper-thread pull-off comprising an operative thread-engaging member fixed upon and rotating with said shaft and timed to act during the dwell of the looper in drawing off a supply of looper-thread.
- In testimony whereof, I have signed my name to this specification, in the presence of two subscribing witnesses.
